DESIGN FOR A MIRROR

Halbert Creston Doner, Toledo, Ohio, assignor to Libbey-Owens-Ford Glass Company, Toledo,
Ohio

Application July 1, 1940, Serial No. 93,377

Term of patent 7 years

To all whom it may concern:

Be it known that I, Halbert Creston Doner, a citizen of the United States, residing at Toledo, in the county of Lucas and State of Ohio, have invented a new, original, and ornamental Design for a Mirror, of which the following is a specification, reference being had to the accompanying drawing, forming part thereof.

Fig. 1 is a perspective view of a mirror showing my new design;

Fig. 2 is an enlarged vertical transverse section therethrough shown broken apart for convenience of illustration; and

Fig. 3 is an enlarged fragmentary perspective view of one corner of said mirror.

I claim:

The ornamental design for a mirror, as shown.

HALBERT CRESTON DONER.
